(57) CLAIM

I claim the ornamental design for a beach towel wrap, as shown and described.

DESCRIPTION

FIG. 1 is a reduced, front perspective view of a beach towel wrap showing my new design as worn;

FIG. 2 is a front elevation view of the beach towel wrap showing portions of the tie straps cutaway for ease of illustration;

FIG. 3 is a top plan view thereof;

FIG. 4 is a rear elevation view thereof;

FIG. 5 is a bottom plan view thereof;

FIG. 6 is a side elevation view thereof; and,

FIG. 7 is a side elevation view of the beach towel wrap, viewed from an opposite side shown in FIG. 6;

FIG. 8 is an exterior plan view of the beach towel wrap shown in FIG. 1; the beach towel wrap shown laid flat; and,

FIG. 9 is an interior plan view of the beach towel wrap, viewed from an opposite side shown in FIG. 8.

The broken lines in FIG. 1 show environmental features, which form no part of the claimed design.
